US0D1014269S

(12) **United States Design Patent** (10) **Patent No.:** **US D1,014,269 S**
(45) **Date of Patent:** **** Feb. 13, 2024**

(54) **COSMETIC JAR**

- (71) Applicant: **The Procter & Gamble Company**,
Cincinnati, OH (US)
- (72) Inventors: **Andrew Dapore**, Cincinnati, OH (US);
Graham Clive Hufton, New York, NY (US)
- (73) Assignee: **The Procter & Gamble Company**,
Cincinnati, OH (US)

(**) Term: **15 Years**

(21) Appl. No.: **29/812,028**

(22) Filed: **Oct. 19, 2021**

(51) LOC (14) Cl. **09-01**

(52) U.S. Cl.

USPC **D9/558**; D9/529

(57) **CLAIM**

The ornamental design for a cosmetic jar, as shown and described.

DESCRIPTION

FIG. 1 is a perspective view of a first embodiment of our new design for a cosmetic jar;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a perspective view of a second embodiment of our new design for a cosmetic jar;

FIG. 9 is a front elevation view thereof;

FIG. 10 is a back elevation view thereof;

FIG. 11 is a left elevation view thereof;

FIG. 12 is a right elevation view thereof;

FIG. 13 is a top plan view thereof; and,

FIG. 14 is a bottom plan view thereof.

The broken lines depict portions of the cosmetic jar that form no part of the claimed design.

1 Claim, 4 Drawing Sheets
